UNITED STATES PATENT OFFICE

JAMES DILLON, OF MOUNT VERNON, NEW YORK

CONNECTER FOR TERMINAL WIRES

Application filed July 28, 1927. Serial No. 209,065.

This invention relates to improvements in connectors for terminal wires, and has for its object to provide a device which may be easily and quickly attached or detached from the thumb nut of post electrodes of spark plugs and the like.

Another object of the invention is to provide a device which is simple in construction, economical and inexpensive to manufacture.

Another object of the invention is to provide a device which is adapted to engage the thumb nut of the spark plug to prevent unintentional displacement in any direction.

Another object is to provide certain improvements in the form, construction and arrangement of the several parts whereby the above named and other objects may be effectively attained.

A practical embodiment of my invention is represented in the accompanying drawings, in which

Fig. 1 represents a plan view of my improved connector applied to the thumb nut of a post electrode of a spark plug.

Fig. 2 represents a front elevation of the same showing the upper portion of a spark plug.

Fig. 3 represents a side elevation of the same.

Fig. 4 represents a rear elevation of the same.

Fig. 5 represents a vertical section taken in the plane of the line V—V, looking in the direction of the arrows.

Fig. 6 represents a blank of sheet metal into which my improved connector is developed.

The upper portion of the spark plug, shown in Figs. 1 to 5 inclusive, comprises the insulator denoted by 1, the screw-threaded post electrode by 2, the lock nut by 3 threaded on the post electrode 2 and the thumb nut 4, also having a threaded engagement with the post electrode 2.

The connector is developed from a blank

5 of sheet metal, such as spring brass or other similar material, shown in Fig. 6, and comprises an elongated rectangular body 6 and a rectangular head 7, which body portion and head are connected by a neck 8. The ends 50 of the elongated body portion 6 are developed into oppositely disposed jaws 9 which are bent substantially at right angles to the body portion. Each of the jaws 9 is curved outwardly at 10 and provided with a series 55 of vertically arranged corrugations 11, interposed between the curved ends and the body, which corrugations are arranged to embrace the thumb nut and hold the jaws securely thereon. The lower edge of each of the jaws 9 is turned inwardly at 12, which edges are arranged to engage upon opposite sides of the bottom of the thumb nut 4 to prevent any unintentional displacement of the jaws from the nut by an upward movement.

60 The head 7 is developed into a tubular member 14 which is bent at the neck 8 so as to be disposed in a horizontal plane overlying the jaws 9, as clearly shown in Figs. 1 70 and 3.

The tubular member 14 is provided with a longitudinal slot 15 so that the ends of the member may be bent to embrace the exterior surface of an insulated terminal wire 75 16 and also to accommodate wires of different diameters. To form an electrical contact with the connector, the wire proper is turned rearwardly on the insulation and the member arranged to engage the insulation so that it will pinch the wire therebetween.

80 By disposing the member 14 over the jaws 9, the terminal wire will be led over the top of the spark plug, the position of which materially facilitates the means of attaching 85 and detaching the connector to the thumb nut of the spark plug.

Furthermore, the structure is extremely rigid and compact and not liable to be readily bent out of shape.

90

It is also to be pointed out that the position of the member 14 with respect to the spring jaws 9 tends to relieve the terminal wire from undue strain while removing the connector from the thumb nut, since the action of removing the connector should the terminal wire be manipulated, would be to push the wire in the member 14.

While I have described my invention as a connector for thumb nuts of the post electrodes of spark plugs, I wish it understood that the connector is equally well adapted for use in connection with thumb nuts of batteries or other electrical apparatus.

It will be understood that various changes may be resorted to in the form, construction and arrangement of the several parts, without departing from the spirit and scope of my invention; and hence, I do not intend to be limited to the details herein shown and described except as they may be included in the claims.

What I claim is:

1. The combination with a spark plug having a thumb nut, of a connector for terminal wires comprising, a body portion developed into oppositely disposed spring actuated jaws arranged to embrace the opposite sides of the thumb nut, each of said jaws having an inturned portion arranged to project under the thumb nut to prevent unintentional lateral displacement, and a wire holding member formed integral with said body portion and positioned to over-hang the thumb nut.

2. The combination with a spark plug having a thumb nut, of a connector for terminal wires comprising, a body portion developed into oppositely disposed spring actuated jaws arranged to embrace the opposite sides of the thumb nut, each of said jaws having an inturned bottom edge arranged to project under the thumb nut to prevent unintentional lateral displacement, and a wire holding member formed integral with said body portion and positioned to over-hang the thumb nut.

3. The combination with a spark plug having a thumb nut, of a connector for terminal wires comprising, a body portion developed into oppositely disposed spring actuated jaws arranged to embrace the opposite sides of the thumb nut, each of said jaws having a series of vertical corrugations disposed to engage the side of the thumb nut and an inturned portion arranged to project under the thumb nut to prevent unintentional lateral displacement, and a wire holding member formed integral with said body portion and positioned to over-hang the thumb nut.

4. The combination with a spark plug having a thumb nut, of a connector for terminal wires comprising, a body portion developed into oppositely disposed spring actuated jaws arranged to embrace the opposite sides

of the thumb nut, each of said jaws having a series of vertical corrugations disposed to engage the side of the thumb nut and an in-turned bottom edge arranged to project under the thumb nut to prevent unintentional lateral displacement, and a wire holding member formed integral with said body portion and positioned to over-hang the thumb nut.

In testimony, that I claim the foregoing as my invention, I have signed my name this 25th day of July, 1927.

JAMES DILLON.
